UNITED STATES PATENT OFFICE.

SAMUEL MCRAE AND JOHN H. BLOM, OF EVERETT, WASHINGTON, ASSIGNEES TO THE
CENTRIFUGAL AEROPLANE COMPANY, OF EVERETT, WASHINGTON, A CORPORA-
TION OF WASHINGTON.

CIRCLE-SWING.

1,124,770.

Specification of Letters Patent.

Patented Jan. 12, 1915.

Application filed November 8, 1913. Serial No. 799,851.

To all whom it may concern:

Be it known that we, SAMUEL MCRAE and JOHN H. BLOM, citizens of the United States, residing at Everett, in the county of Snohomish, State of Washington, have invented new and useful Improvements in Circle-Swings, of which the following is a specification.

Our invention relates to that class of amusement devices which employs aeroplanes in connection with cars that are secured to a central rotative drum about which they are constrained to move by restraining cables connecting each car with the drum. The device thus resembles a circle swing in which planes are mounted on the cars to support them after they leave the speedway or trackway, over which they travel, by reason of the increased speed of revolution coupled with the action of the centrifugal force developed.

The object of our invention is to provide an amusement device which shall simulate traveling by an automobile at increasing speed and concluding with a trip through the air, returning to the place of starting by a smooth, gliding movement.

The construction and operation are simple, safe, and secure, and the device is under absolute control so as to eliminate as fully as possible the dangers which are so frequently associated with high-speed automobiles and free aeroplanes.

That of which our invention consists will be particularly set forth in the claims terminating this specification.

In the accompanying drawings we have shown our invention embodied in the form now preferred by us.

Figure 1 shows a plan view of our invention with the parts in position of rest. Fig. 2 is a similar view with the parts in position of motion. Fig. 3 is an elevation of one side of the device with the parts in position of rest. Fig. 4 is an elevation of the same character except that the parts are in position of motion. Fig. 5 is a plan view of a car showing the speedway or trackway upon which it runs, and showing also the manner of attaching the controlling lines to the car. Fig. 6 is an elevation of such a car upon the trackway, the trackway and the inner wall or abutment being shown in section. Fig. 7

shows the guide sheaves for the tension lines and the tension weight.

The construction which we at present prefer and have chosen for illustration, is as follows: A central tower 1 has a central shaft 1 mounted to turn in bearings and at its upper end carrying a drum or wheel 10 of considerable diameter. This shaft and drum are to be turned by any suitable application of power. As the manner of applying power thereto is largely immaterial, we have not shown the power plant.

Surrounding the tower and concentric thereto, is a trackway 2, which has been shown as approximately level, although it may be banked if desired. This trackway should have a smooth surface, such for instance as may be given to concrete or asphalt construction, and should have an inner marginal wall or outwardly facing trackway 20, the outer face of which should be truly concentric with the axis of rotation 75 of the drum shaft 11. We also prefer that this be provided with a wheel-receiving groove 21 in its outwardly facing surface, for the reception of a wheel of the car.

A series of cars 4 is provided and each car has wheels 40 for running on the horizontal trackway, and a horizontally facing wheel 41 adapted to engage the outwardly facing surface of inner wall 20. When this wall face is provided with a groove 21, the 80 wheel 41 would enter said groove.

The detailed construction of the cars (which are wedge-shaped) is not shown except that each car has a frame 42 and wheels 40 and 41, and forward and aft means for 90 attachment of the lines. The axles for wheels 40 are fixedly secured to the cars in a position radial to the tower. The passenger-accommodating means are not illustrated as these may be made of anything found 95 suitable and their character has no essential relation to our invention. The car is provided with one or more lifting planes, as 6 and 60, which may be of any suitable construction. With proper proportioning and 100 construction, no provision for adjustment when in use is needed.

From the periphery of wheel or drum 10 extend two main or restraining lines 3 to each car, connected to opposite ends of the 105 car as shown in Fig. 5. From each car

frame to the frame of car next ahead and behind extend spacing lines 51, which should be slightly longer than needed to connect consecutive cars.

5 From wheel or drum 10 extends a series of tension lines 5 connecting with spacing lines 51 at a point about half way between cars. The tension lines 5 connect at one end with spacing lines 51, and at the other end 10 pass through sheaves 7, which are suspended from the drum 10, so that the sheaves may turn and swing in accordance with the direction of lead of the tension lines. The point of connection of the tension lines with the 15 drum 10, through the medium of sheaves 7, is about ninety degrees back of the point where the main or restraining lines 3 of the adjacent cars are attached. The inner ends 20 of all tension lines are secured to a weight 50, which may rise and fall and which thus maintains a constant tension upon all lines and a uniform position for all.

The operation of our device is as follows: The parts when at rest will occupy the position shown in Figs. 1, 3, 5, and 6, the cars 25 resting upon the trackway and held against the vertical wall 20 at the inner side of the trackway, by the tension communicated through the tension lines 5. The tension 30 weight 50 will be in its lowermost position. The lines will lead to the wheel or drum 10, in the manner shown in Fig. 1, the tension lines 5 being substantially radial and the main lines 3 substantially tangential to the 35 drum. In this position of the main lines, power is applied to the wheel or drum 10, to produce a pull upon the cars in a direction to one side of the normal, in an amount proportioned to the radius of the drum. As 40 the resistance to movement of the cars will be reduced to a minimum, this will be sufficient to start the cars in motion. As the cars acquire speed centrifugal force will be developed which will cause them to pull out 45 from the wall 20 and will also tend to advance the restraining lines in their angular position relative to the drum 10, approaching to positions where the main lines are more nearly radial to the drum. As the 50 cars draw out from the wall 20, they separate slightly from each other, but this is compensated by the spacing lines 51 drawing more nearly straight. As this occurs, the tension lines are drawn out and the weight 55 50 raised. When the cars reach a certain velocity, the foreign power is disconnected from the wheel or drum 10 and the cars are kept in motion by their own momentum, and the action of the planes upon the air will 60 have caused them to rise from the trackway, in which condition the frictional resistance will be reduced and an increase in speed of movement will be possible. When under full movement in the air, the cars will advance 65 angularly upon the drum and the

main lines 3 approach more nearly to a radial position as shown in Fig. 2. This will also permit the cars to fly at somewhat greater distance from the tower. As the momentum is expended, the speed of movement through the air is lessened and the strain upon all lines is reduced, the cars descend to the trackway by a very gentle, gliding movement similar to the alighting of a bird, and when at rest the cars and lines 70 are in the same relative position as at starting, as shown in Figs. 1, 3, 5, and 6.

While the planes are close to the trackway, the air which is downwardly impelled by the angle of the planes, is resisted by the 75 trackway and exerts a greater lifting effect than it does when the plane has lifted to a higher level. This feature acts as an automatic means to prevent the planes from rising 80 far from the trackway.

We also provide what we call an altitude 85 line, 8, which connects all the main lines at a certain distance from the center. The length of the connecting sections of this line is made such that it becomes taut when the 90 outward movement of the cars reach a certain position, after which the altitude lines will not permit their going farther.

By reason of the change in angular position of the main lines between positions of 95 rest and motion, the points of connection of the altitude line with the main lines will be nearer the tower when cars are at rest than when they are in motion. In consequence, the sections of the altitude line become slack and 100 these points are capable of drawing to higher levels when the cars are at rest than they will occupy when under full motion. As soon as the cars move out sufficiently to tighten the altitude line, the main lines at 105 these points will be drawn down. The difference in the position of the main lines under these conditions is shown in Figs. 3 and 4.

The fact that two restraining lines 3 are 110 secured to each car, and that the points of attachment of these are at points considerably separated fore-and-aft, serves to keep the car pointed in the right direction. The point of attachment of these lines to the car 115 should preferably be slightly above the center of action of the centrifugal force developed, so that there will be a slight banking of the aeroplane sufficient to give it a certain tendency to fly in a curve.

The connection of the aeroplanes in an 120 endless chain by the spacing lines 51, keeps them at proper and regular intervals. The connection of these lines at forward and rearward points of the frame and the yielding tension strain maintained thereon, tend to prevent fore-and-aft dipping of the aeroplanes, thus securing steady, even flight.

It is evident that many changes may be 125 made in the detail of construction of our 130

device without changing the principles employed. The construction which has been described in detail is not the only one which it is intended our invention shall cover, but only that which is now preferred by us.

We claim as our invention—

1. An amusement device comprising a series of aeroplanes and lines directly connecting them to form an endless chain there-
10 of, means for propelling the aeroplanes, and means for controlling their movement within a circular path comprising lines ex-
tending from each aeroplane to a central point.
- 15 2. An amusement device comprising a se-
ries of aeroplanes and lines directly connecting them in an endless chain, and a re-
volving anchorage to which all the aero-
planes are connected by restraining and
20 driving lines.
- 25 3. An amusement device comprising a se-
ries of aeroplanes and lines connecting them in an endless chain, a revolving anchorage to which all the aeroplanes are connected by horizontally extending restraining and driving lines, and means restraining the aeroplanes to movement without a given circle.
- 30 4. An amusement device comprising a se-
ries of aeroplanes and lines connecting them in an endless chain, a revolving anchorage to which all the aeroplanes are connected by restraining and driving lines, and a circular trackway for the aeroplanes having an
35 outwardly facing trackway surface.
- 40 5. An amusement device comprising a se-
ries of aeroplanes and lines connecting them in an endless chain, a revolving anchorage to which all the aeroplanes are connected by restraining and driving lines, and a circular trackway for the aeroplanes having both upwardly facing and outwardly facing
45 trackway surfaces.
- 50 6. An amusement device comprising a se-
ries of aeroplanes and lines connecting them to form an endless chain, a circular track-
way having both upwardly facing and out-
wardly facing trackway surfaces, wheels
carried by the aeroplanes for engaging both
55 said trackway surfaces, lines extending
from the aeroplanes toward the center, and
a rotative member to which said lines are
attached at a distance from the center.
- 60 7. An amusement device comprising a se-
ries of aeroplanes and lines connecting them to form an endless chain, means for produc-
ing a yielding tension on said connecting
lines, a circular trackway having both up-
wardly facing and outwardly facing track-
65 way surfaces, wheels carried by the aero-
planes for engaging both said trackway sur-
faces, lines extending from the aeroplanes
toward the center, and a rotative member to
which said lines are attached at a distance
from the center.

8. An amusement device comprising a se-
ries of aeroplanes, lines extending from the
aeroplanes toward a common central point,
an elevated revoluble member to which the
inner ends of said lines are connected at a
70 distance from its center of revolution, and
means independent of the radially extend-
ing lines for maintaining the spacing be-
tween the aeroplanes.

9. An amusement device comprising a se-
ries of aeroplanes, lines extending from the
aeroplanes toward a common central point,
an elevated revoluble member to which the
inner ends of said lines are connected at a
75 distance from its center of revolution, and
spacing lines connecting the aeroplanes in
an endless chain.

10. An amusement device comprising a se-
ries of aeroplanes, lines extending from the
aeroplanes toward a common central point,
80 an elevated revoluble member to which the
inner ends of said lines are connected at a
distance from its center of revolution, spac-
ing lines connecting said aeroplanes in an
endless chain, and tension means applied to
85 said spacing lines.

11. An amusement device comprising a se-
ries of aeroplanes, spacing lines connecting
the aeroplanes to form an endless chain,
lines extending from each aeroplane toward
a common center, a rotative wheel to the pe-
riphery of which said latter lines are con-
nected, tension lines connecting the spacing
lines with the said rotative wheel, guides
carried by said wheel through which the
90 tension lines pass, and a tension-producing
weight secured to said tension lines.

12. An amusement device comprising a se-
ries of aeroplanes, spacing lines connect-
ing the aeroplanes to form an endless chain,
a rotative member placed centrally of said
aeroplanes, and tension lines connecting
95 said spacing lines with said central rota-
tive member.

13. An amusement device comprising a se-
ries of aeroplanes, spacing lines connect-
ing the aeroplanes to form an endless chain,
tension lines extending from each spacing
line to a central point, and a yielding ten-
100 sion-producing means acting upon all the
tension lines.

14. An amusement device comprising a se-
ries of aeroplanes, spacing lines attaching
said aeroplanes in series to form an endless
chain, the points of connection of said lines
105 with the aeroplane frames being at points
considerably separated from front to rear,
means for propelling said aeroplanes and
means for constraining their movement
within determined circular paths.

15. An amusement device comprising a se-
ries of aeroplanes, spacing lines attaching
said aeroplanes in series to form an end-
less chain, the points of connection of said
lines with the aeroplane frames being at
110 115 120 125 130

- points considerably separated from front to rear, combined restraining and driving lines extending from the aeroplanes to the central part of their path of movement, and 5 a rotative member to which said lines are connected.
16. An amusement device comprising a series of aeroplanes, spacing lines connecting said aeroplanes to form a continuous 10 chain, restraining lines connecting with front and rear points of the aeroplane frame and extending from said points to a central point.
17. An amusement device comprising a series of aeroplanes, spacing lines connecting said aeroplanes to form a continuous 15 chain, restraining lines connecting with front and rear points of the aeroplane frame and extending from said points to a central point, and means for driving the aeroplane 20 through said restraining lines.
18. An amusement device comprising an aeroplane, two restraining lines connected with the aeroplane at points which are, respectively, toward the front and rear of the 25 aeroplane frame, and a horizontally distant anchorage connection with said lines.
19. An amusement device comprising an aeroplane, two restraining lines connected with the aeroplane at points which are, respectively, toward the front and rear of the 30 aeroplane frame, a horizontally distant anchorage connection for said lines, and means for moving said anchoring point about a 35 center.
20. An amusement device comprising an aeroplane, a restraining line extending from the aeroplane to a horizontally distant anchorage, the connection of said lines with the aeroplane being at a point slightly above the 40 center of gravity of the aeroplane, to thereby produce a slight banking of the aeroplane.
21. An amusement device comprising an aeroplane, a pair of restraining lines respectively connected with the aeroplane at points which are materially separated from front to rear and slightly above the center of 45 gravity of the aeroplane, and a horizontally distant anchorage connection for said lines.
22. An amusement device comprising an aeroplane, a pair of restraining lines respectively connected with the aeroplane at points which are materially separated from front to rear and slightly above the center of 55 gravity of the aeroplane, and a member rotative about a vertical axis to which the distant ends of the restraining lines are connected at a distance from its axis of rotation.
23. An amusement device comprising a series of aeroplanes, a pair of restraining lines connecting with each aeroplane, respectively at front and rear parts of the frame 60 thereof, spacing lines connecting the front and rear of the aeroplanes to form an endless chain, and a centrally placed member to which all of said restraining lines are connected.
24. An amusement device comprising a series of aeroplanes, a pair of restraining lines connecting with each aeroplane, respectively at front and rear parts of the frame thereof, spacing lines connecting the front and rear of the aeroplanes to form an 70 endless chain, a centrally placed member to which all of said restraining lines are connected, tension lines connected with the middle part of the spacing lines and extending to the center, and a tension-producing 75 means connected with the inner ends of the tension lines.
25. An amusement device comprising a series of aeroplanes, a central tower, a rotative member at the top of said tower, restraining lines connecting said rotative member with the respective aeroplanes, and an altitude line connecting intermediate 80 parts of all the restraining lines.
26. An amusement device comprising a series of aeroplanes, a central tower, a rotative member at the top of said tower, restraining lines connecting said rotative member with its respective aeroplanes, and an altitude line connecting intermediate 85 parts of all the restraining lines, said altitude line hanging slack between the restraining lines while the aeroplanes are stationary and becoming taut when the aeroplanes get in full flight.
27. An amusement device comprising a series of aeroplanes, a central elevated tower, a wheel or drum-like member of material diameter secured to turn about a vertical axis at the top of the tower, restraining lines connecting each aeroplane with the periphery of said wheel, spacing lines connecting successive aeroplanes to form an 90 endless chain, tension lines connected with said spacing lines, guides carried by said 95 wheel through which the tension lines pass, and yielding tension-producing means secured to the inner ends of said tension lines.
28. An amusement device comprising a series of aeroplanes, a central elevated tower, a wheel or drum-like member of material diameter secured to turn about a vertical axis at the top of the tower, restraining lines connecting each aeroplane with the periphery of said wheel, spacing lines 100 connecting successive aeroplanes to form an endless chain, tension lines connected with said spacing lines, sheaves flexibly supported from said wheel through which the tension lines pass, and a weight secured to the 105 inner ends of the tension lines.
29. An amusement device comprising a series of aeroplanes, a central elevated tower, a wheel or drum-like member of material diameter secured to turn about a vertical 110 axis at the top of the tower, restraining lines connecting each aeroplane with the periphery of said wheel, spacing lines 115 connecting successive aeroplanes to form an endless chain, tension lines connected with said spacing lines, sheaves flexibly supported from said wheel through which the tension lines pass, and a weight secured to the 120 inner ends of the tension lines.
30. An amusement device comprising a series of aeroplanes, a central elevated tower, a wheel or drum-like member of material diameter secured to turn about a vertical 125 axis at the top of the tower, restraining lines connecting each aeroplane with the periphery of said wheel, spacing lines connecting successive aeroplanes to form an endless chain, tension lines connected with said spacing lines, sheaves flexibly supported from said wheel through which the tension lines pass, and a weight secured to the 130 inner ends of the tension lines.

tical axis at the top of the tower, restraining lines connecting each aeroplane with the periphery of said wheel, spacing lines connecting successive aeroplanes to form an 5 endless chain, tension lines connected with said spacing lines, guides carried by said wheel through which the tension lines pass, the tension and restraining lines for like aeroplanes leading to points on said wheel separated 10 by a material peripheral angle, and tension-producing means connected with the tension lines.

30. An amusement device comprising a series of aeroplanes, spacing lines connecting them in an endless chain, a central elevated tower, a wheel of material diameter mounted to turn about a vertical axis at the top of the tower, restraining and driving lines connecting the periphery of said wheel 15 with the aeroplanes, a trackway for the aeroplanes, an outwardly facing trackway, and a side facing wheel carried by each aeroplane and adapted to engage said outwardly facing trackway.

25 31. An amusement device comprising a series of aeroplanes, spacing lines connecting them in an endless chain, a central elevated tower, a wheel of material diameter mounted to turn about a vertical axis at the top of the tower, restraining and driving lines connecting the periphery of said wheel 30 with the aeroplanes, an altitude line connecting all of the restraining lines at a point intermediate their length, a trackway 35 for the aeroplanes, an outwardly facing circular trackway, and a side facing wheel carried by each aeroplane and adapted to engage said outwardly facing trackway.

32. An amusement device comprising a 40 series of aeroplanes, spacing lines connecting them in an endless chain, a central elevated tower, a wheel of material diameter mounted to turn about a vertical axis at the

top of the tower, restraining and driving lines connecting the periphery of said wheel 45 with the aeroplanes, tension lines connected with the spacing lines, guides on the rotative and driving wheel receiving the tension lines at points back from the points of attachment of the restraining lines for corresponding aeroplanes, a weight carried by the inner ends of the tension lines, a trackway for the aeroplanes, an outwardly facing circular trackway, and a side facing wheel carried by each aeroplane and adapted 50 to engage said outwardly facing trackway.

33. An amusement device comprising a circular trackway having a raised wall about its inner edge the outwardly facing 55 surface of said wall being circular and forming a supplemental trackway, an aeroplane having wheels to engage the horizontal and vertical trackways, restraining lines extending from the aeroplane inward, and means whereby the aeroplane may move outward from said wall as the aeroplane 60 acquires speed.

34. An amusement device comprising a circular trackway having a raised wall 65 about its inner edge the outwardly facing surface of said wall being circular and forming a supplemental trackway, an aeroplane having wheels to engage the horizontal and vertical trackways, restraining lines extending from the aeroplane inward on lines diverging forwardly of a radius, and means for producing a strain upon said 70 restraining lines and for maintaining their direction forward of a radius.
